UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

COLLAR-TIPPER.

No. 904,398.

Specification of Letters Patent.

Patented Nov. 17, 1908.

Application filed June 19, 1907. Serial No. 379,739.

To all whom it may concern:

Be it known that I, WILLIAM BARTHOLOMEW, citizen of the United States, residing at Chicago, county of Cook, and State of Illinois, have invented certain new and useful Improvements in Collar-Tippers, of which the following is a specification, reference being had therein to the accompanying drawing.

10 This invention relates to a collar tipper, and particularly to a machine for simultaneously bending the opposite tips of a collar.

The invention has for an object to provide a novel construction and arrangement 15 of the collar supporting shoe and the steam chest into contact with which the collar to be tipped is carried.

A further object of the invention is to provide a novel and improved construction 20 of operating means for the shoe by which a plurality thereof may be used and one automatically lowered as the other is raised thus enabling an operator to control two tipping devices.

25 Other and further objects and advantages of the invention will be hereinafter set forth and the novel features thereof defined by the appended claims.

In the drawings:—Figure 1 is a front elevation of the machine; Fig. 2 is a side view thereof; Fig. 3 is a top plan; Fig. 4 is a front elevation of the supporting shoe; Fig. 5 is a side elevation thereof with a collar applied; Fig. 6 is a top plan thereof; Fig. 35 7 is a top plan of the steam chest with parts in section on the line 7—7, Fig. 8; Fig. 8 is a front elevation of this chest with parts in section on the line 8—8, Fig. 7, and Fig. 9 is a vertical section on the line 9—9, Fig. 8.

40 Like numerals refer to like parts in the several views of the drawings.

In the drawings, the numeral 1 designates a standard which may be of any desired character or configuration and provided with 45 the supporting base 2. At the upper end of this standard a steam chest 3 is attached thereto and may extend to one or both sides of the standard as may be desired. This standard is provided at its upper portion 50 with a steam chamber 4 therein having the inlet pipe 5 at its upper portion and drain pipe 6 at its lower portion, both of these being suitably valved for controlling the same. The inlet 5 communicates with the 55 main steam supply pipe 7 which is provided

with a valve at 8 and communicates at 9 with the steam chest 3 from which a drain connection 10 extends at the bottom thereof. The steam chamber in the standard is provided for the purpose of supplying dry steam to a moistener 11 of any desired character which is provided with the controlling valve 12 so that the tips of the collars may be moistened prior to the pressing operation.

The pressing operation is effected by a 65 supporting shoe 13 which is brought into contact with the pressing surface 14 of the steam chest 3. This surface 14 is formed of proper shape to simultaneously bend the opposite tips of the collar when supported 70 by the shoe 13. The shoes are slidably mounted upon tracks or ways 15 carried by the laterally extending brackets 16 which are carried by the upper end of the supporting rods 17 of the shoes and held against rotation thereon by pin 18 extending through an eye 19 in the bearing sleeve or collar 20 carried by the standard. The shoe is provided with a slide block 21 at its lower portion embracing the way 15. The rod 17 is 80 guided by collar 20 from the standard and also by the collar 22 thereon. Below this bearing collar, a toggle 23 is provided comprising the angle arm 24 of the treadle 25 and the toggle link 26 extending from said 85 angle arm and pivoted at 27 to the lower end of the rod 17. This link is provided with a cushioning spring 28 which contacts with a bearing on the stem 29 at one end of the link and is secured to the pivoted coupling 30 90 at the opposite end which is recessed to receive stem 29 so as to permit a cushioning compression of the spring as the shoe is forced into the steam chest thus holding the collar under tension during the pressing 95 action. The return movement of these parts is also cushioned by spring 31 resting upon the collar 22 of the standard and adapted to be engaged by the set collar 32 carried by the standard and compressed in its downward movement so that no shock is given 100 in the fall of the shoe by gravity when the toggle connection is broken.

I have illustrated in this case two tipping devices carried by the same standard, and 105 they are substantially identical in construction and adapted for alternate operation, one thereof being automatically lowered as the other is raised into pressing relation. This is accomplished by means of the lever 110

33 pivotally mounted in the lug 34 in the standard, and provided at opposite ends with the heads 35 adapted to engage the contact faces 36 of the angle arms 24 of the 5 toggle lever. It will thus be seen that when the treadle is thrown downward to lift one of the tippers this contact face engages the head of the lever 33 oscillating it so that its head at the opposite end engages the contact face on the toggle at that end to break joint therein and automatically lower the shoe from the steam chest.

When a plurality of steam chests 3 are used they may be connected together by a 15 passage 37 with which inlet and outlet connections 9 and 10 communicate, and the inclined walls 14 of the pressing surfaces of the chest are merged into an intermediate V-shaped tongue 38 which also tapers longitudinally and is adapted to fit between the 20 separated faces 39 of the shoe 13, these faces being disposed diagonally to each other. These faces may, if desired, be provided upon their outer surface with a rubber covering 40 to prevent injury to the finished surface of the collar, and also with a cloth outer covering 41, as shown in Figs. 1 and 5, so that the inner surface of the tip is not brought into contact with the metal of the 25 shoe. The faces 39 are supported by a U-shaped frame of the shoe 13 which is closed at one end by the plate 42 having a slot 43 therein into which the tabs of the collar may enter when the same is applied to the shoe. 30 The shoe is also provided with an operating handle 44 by which it may be conveniently slid upon the way 15.

In the operation of the invention, the collar to be tipped may be first moistened at the 40 steam nozzle provided for that purpose, and then the body of the collar is disposed between the faces of the supporting shoe, as shown in Fig. 6, with the tips resting upon these faces as in Fig. 5, when the treadle at 45 that side of the machine is thrown downward and the collar tips brought under tension into contact with the pressing faces of the steam chest, while the tongue which enters between the fold line supports holds 50 the collar in contact therewith while the tips are pressed. They are allowed to stand in this contact for the proper length of time and will then be automatically withdrawn by throwing downward the treadle of the 55 opposite tipper shoe so that the lever connection breaks joint with the first mentioned tipper toggle permitting it to fall by gravity so that the collar may be readily removed therefrom. A machine is thus produced in 60 which one operator can attend the two tipping devices thus largely increasing the capacity thereof, and by means of the rigid shoe for supporting the collars the opposite surfaces are always retained in the same relation to each other and a uniform angle of

bend thus secured upon the tips. This shoe is also slidably supported for removal laterally of its actuating rod so as to be brought into convenient position for the insertion of the collar by the operator. The collar can 70 thus be handled by means of the tabs and any danger of injury to the ironed surface thereof in handling avoided.

It will be seen that with this construction of machine provision is made both for the 75 moistening and pressing the tips so that this operation can be performed by the same operator and immediately in succession with each other.

By a proper construction of the pressing 80 members this invention may be used for pressing other articles than collars.

Having described my invention and set forth its merits, what I claim and desire to secure by Letters Patent is:—

1. In a collar tipper, a steam chest, a collar support having spaced relatively fixed downwardly inclined collar tip supports and tip fold line supporting surfaces diverging from each other, and means for bringing 90 said support and chest into contact.

2. In a collar tipper, a steam chest, opposite tip supporting members having tip fold line supports in fixed relation to and diverging from each other, and means for moving 95 one of said parts toward the other.

3. In a collar tipper, a steam chest, opposite tip supporting members having tip fold line supports in fixed relation to and diverging from each other, means for moving one 100 of said parts toward the other, and means for shifting said support laterally of its movement toward said chest.

4. In a collar tipper, a steam chest, opposite tip supporting members having tip fold line supports in fixed relation to and diverging from each other, means for moving one 105 of said parts toward the other, means for shifting said support laterally of its movement toward said chest, and a tongue carried by said chest to extend between the diverging walls of said fold line supports.

5. In a collar tipper, a steam chest having oppositely inclined pressing walls and an intermediate tongue with diverging walls, a 110 collar tip support having spaced oppositely inclined tip fold line supports diverging from each other to receive said tongue intermediate thereof, and means for moving one of said parts relatively to the other.

6. In a collar tipper, a collar tip support having inclined pressing faces and tip line fold supports spaced from each other to support the separated ends of a collar, a steam chest having oppositely inclined pressing 115 walls and an intermediate tongue constructed to traverse the space between said supports, and means for moving one of said parts relative to the other.

7. In a collar tipper, a collar tip support 120

having inclined pressing faces and tip line fold supports spaced from each other to support the separated ends of a collar, a steam chest having oppositely inclined pressing 5 walls and an intermediate tongue constructed to traverse the space between said supports, means for moving one of said parts relative to the other, and a cushioning surface upon the pressing faces beneath the fold 10 line support.

8. In a collar tipper, a collar tip support having inclined pressing faces and tip line fold supports spaced from each other to support the separated ends of a collar, a steam 15 chest having oppositely inclined pressing walls and an intermediate tongue constructed to traverse the space between said supports, means for moving one of said parts relative to the other, a fabric covering 20 upon the face of said support, and a cushioning surface inset upon said pressing faces beneath the fold line support and said covering.

9. In a collar tipper, a steam chest having 25 oppositely inclined walls and an intermediate V-shaped tongue tapered longitudinally, a support comprising separated inclined surfaces disposed diagonally to each other in alinement with the walls of said tongue, 30 and means for moving one of said parts relatively to the other.

10. In a collar tipper, a steam chest having oppositely inclined walls and an intermediate V-shaped tongue tapered longitudinally, 35 a support comprising separated inclined surfaces disposed diagonally to each other in alinement with the walls of said tongue, and means for moving one of said parts into and out of alinement with the 40 other.

11. In a pressing apparatus, a standard, a fixed steam chest at the upper end thereof, a bearing sleeve carried by said standard, a reciprocating rod mounted in said sleeve, 45 an article support carried by the upper end of said rod, a treadle mounted upon the base of said standard and having an angle arm, a link between said treadle arm and rod comprising a pivoted member having a 50 stem provided with a bearing for a spring and a coöperating pivoted member carrying a spring surrounding said stem and engaging said bearing thereon, a collar carried by said rod, and a spring disposed between 55 said collar and the upper surface of said bearing sleeve.

12. In a pressing apparatus, a standard, a fixed steam chest at the upper end thereof, bearing sleeves carried by said standard, a 60 reciprocating rod mounted in said sleeves, an article support carried by the upper end of said rod, a treadle mounted upon the base of said standard, an intermediate link between said treadle and rod provided with 65 a cushioning device to hold the support in

contact with the chest under yielding pressure, a collar carried by said rod, a spring disposed between said collar and the upper surface of one of said bearings, a laterally extending way carried by the upper end of 70 said rod, means upon the collar support to travel upon said way, an eye carried by one of said bearings, and a pin extending from said way through said eye.

13. In a pressing apparatus, a plurality of 75 steam chests, a plurality of article supports, means for moving one of each of said parts toward the other, and shifting means disposed to engage said moving means in their travel to automatically lower one support 80 as another is raised.

14. In a pressing apparatus, a standard, a plurality of steam chests supported thereby, a plurality of article supports adapted to travel toward and from said steam chests, 85 treadle levers and connections for actuating said supports, and a shifting lever adapted to alternately engage said treadle lever connections in the movement of an adjacent one thereof.

15. In a pressing apparatus, a standard, a plurality of steam chests carried thereby, article supports mounted for travel toward and from said steam chests, rods for actuating said supports, treadles having a toggle 95 connection with said rods, and a laterally disposed shifting lever disposed in alinement with the joint of said toggles to be actuated thereby as one of the supports is 100 raised.

16. In a pressing apparatus, a standard, a plurality of steam chests carried thereby, article supports mounted for travel toward and from said steam chests, rods for actuating said supports, treadles having a toggle 105 connection with said rods, a shifting lever pivoted upon the standard and provided at opposite ends with heads, and contact plates carried by said treadle levers to engage and move the shifting lever in the 110 travel of the treadles.

17. In a pressing apparatus, a standard having a head provided with a lateral steam passage, supply and drain connections from said passage, a steam chest at the outer end 115 of said passage having a portion of its bottom inclined toward said passage and communicating therewith and oppositely inclined pressing faces with an intermediate tongue upon the under surface of said chest 120 the sides of which converge longitudinally, and an article support coöperating with said faces and tongue.

18. In a collar tipper, a standard, a hollow steam chest secured to the upper portion 125 thereof and extending at opposite sides, inlet and drain connections with said chest, oppositely inclined pressing surfaces carried by the inner face of said chest, and collar tip supporting members inclined to co- 130

- operate with said chest and having diverging fold line supports.
19. In a collar tipper, a collar support comprising an open frame having at its upper end inclined pressing faces, and diverging fold line supports relatively fixed and separated from each other.
20. In a collar tipper, a collar support comprising a U-shaped frame having at its upper end inclined pressing faces, diverging fold line supports relatively fixed and separated from each other, and a wall at one end of said support having a downwardly extending slot from the upper edge thereof.
21. In a collar tipper, a collar support comprising a U-shaped frame having at its upper end inclined pressing faces, diverging fold line supports relatively fixed and separated from each other, a wall at one end of said support having a downwardly extending slot from the upper edge thereof, a slide carriage upon the lower portion of said support, and an operating handle disposed intermediate of the support and carriage.
22. In a pressing apparatus, pressing members, a plurality of article supports, a plurality of means for moving said supports

relative to said pressing members, and an independent device extending from one of said moving means into the path of the other and adapted to be actuated by one of said means for operating another of said means in alternation therewith.

23. In a collar tipper, a pressing member, a supporting member having tip pressing surfaces, and diverging tip fold line surfaces spaced from and in fixed relation to each other to permit the introduction of a collar body between said surfaces.

24. In a collar tipper, a support having tip supporting surfaces, diverging tip fold line supporting surfaces spaced from and in fixed relation to each other, a pressing member having side walls to engage said tip surfaces, and an intermediate diverging tongue having side walls parallel to the walls of the fold line supporting surfaces and adapted to enter between the same.

In testimony whereof I affix my signature in presence of two witnesses.

WILLIAM BARTHOLOMEW.
